DETACHABLE SUN VISOR FOR
AUTOMOBILES

Henry Abrams, Minneapolis, Minn., assignor to
Henry Manufacturing Co., Minneapolis, Minn.,
a corporation of Minnesota

Application May 6, 1948, Serial No. 146,200

Term of patent 3½ years

(Cl. D14—6)

To all whom it may concern:

Be it known that I, Henry Abrams, a citizen of the United States, residing at Minneapolis, in the county of Hennepin and State of Minnesota, have invented a new, original, and ornamental Design for a Detachable Sun Visor for Automobiles, of which the following is a specification, reference being had to the accompanying drawing, forming part thereof.

Referring to the drawing:

Fig. 1 is a perspective view of a detachable sun visor for automobiles, showing my new design;

Fig. 2 is a transverse section taken substantially on the line 2—2 of Fig. 1; and

Fig. 3 is a side perspective view thereof.

* The dotted line showing in Fig. 3 is for illustrative purposes only.

I claim:

The ornamental design for a detachable sun visor for automobiles, as shown and described.

HENRY ABRAMS.
